UNITED STATES PATENT OFFICE.

CHARLES W. McLAUGHLIN, OF GARRETT, INDIANA.

RIM-CEMENTING APPARATUS.

1,098,951.

Specification of Letters Patent. Patented June 2, 1914.

Application filed June 27, 1911. Serial No. 635,636.

To all whom it may concern:

Be it known that I, CHARLES W. McLAUGHLIN, a citizen of the United States, residing at Garrett, in the county of Dekalb and State of Indiana, have invented new and useful Improvements in Rim-Cementing Apparatus, of which the following is a specification.

This invention relates to an apparatus for applying cement or shellac to the rim of a bicycle or automobile rim, the object of the invention being to provide a device of this character wherein the cement will be applied evenly to all the surface of the concave rim of the wheel.

Another object of the invention is to provide an apparatus of this character embodying a receptacle which is normally closed so as to prevent the hardening or evaporation of the cement.

With the above objects in view, and others which will appear as the nature of the invention progresses, the improvement resides in the novel construction and arrangement of parts hereinafter fully described and claimed.

In the drawings, accompanying this specification, there has been illustrated a simple and approved apparatus constructed in accordance with the present invention, it being understood that the showing therein is merely illustrative and that changes in the minor details of construction, as fall within the scope of the appended claim, may be resorted to if desired.

In the drawings, Figure 1 is a view of the improvement, and illustrating the manner of applying the cement to the rim of a wheel. Fig. 2 is a transverse sectional view taken through the apparatus when in its closed position. Fig. 3 is a similar view taken transverse to the showing in Fig. 2.

The improvement comprises essentially a divided casing which, when the members are assembled, provide a substantially circular structure. The casing comprises what may be termed a lower or body portion 1 and a top 2. The top 2 is hingedly connected with the body 1 as at 3 and the meeting edges of both the top and the body are preferably flanged as at 4, the said flanges extending a suitable distance beyond both the body and the top. The projecting portions of both of the flanges are preferably bifurcated, and positioned between the slotted extension 4' of the flange of the body mem-

ber is a pivoted threaded element 5. This element 5 is adapted to be swung between the bifurcated portion of the flange 4 of the top or cover 2. The pivoted member 5 is threaded as at 6 and the said threads are adapted to be engaged by a thumb nut 7 whereby the top is securely retained upon the bottom member 1. The space between the flanges 4 of both of the sections is provided with a compressible gasket 8, the same being connected with the flange 4 of the bottom 1 in any desired manner, and the said gasket engaging all of the edges of the bottom member 1. By this arrangement it will be noted that the shellac or cement which is adapted to be positioned within the bottom 1 is prevented from evaporating, as the top, when sustained upon the bottom, hermetically seals the device. The bottom 1 is preferably provided with legs 9 whereby the same may be supported upon any level surface. The side edges of the bottom 1 adjacent its flange 4, is provided with suitable upstanding bearings 9, the same being adapted to receive trunnions 10 formed upon a delivery roller or wheel 11. This wheel 11 is of a lesser diameter than the casing of the apparatus and has its periphery rounded, so as to snugly engage the depressed periphery of a bicycle or automobile rim. The separate portions upon the opposite faces of the roller or wheel 11 are formed with bosses 12 and 13, and each of the said bosses is provided with an annular depression to provide means whereby the cement or shellac rolling from the sides of the wheel 11 will be again delivered into the bottom section 1 without danger of contacting with the trunnions 10 of the said wheel. The top member 2 is preferably formed with a depressed portion or pocket 14, the same being arranged upon the opposite sides of the said top and are adapted to fit over the bearings 9 of the bottom section 1. The wheel 11 may, if desired, be provided with a coating of some suitable material such as a cloth or the like, as designated by the numeral 15, and this cloth or other fibrous material will serve as a brush for freely delivering the cement to the rim of the bicycle or automobile wheel when the latter is revolved around the roller or wheel 11. The wheel 11, may, if desired, be provided with a plurality of core openings 16, the latter serving to lighten the roller or wheel 11, as well as to serve as pockets for retaining a certain quantity of

the shellac which will enter therein through the previous cover 15, and it will also be evident that a lubricant may be readily applied within the bearings 9 so as to permit of the 5 free revolutions of the trunnions 10 and from the wheel 11.

From the above description, taken in connection with the accompanying drawings, the simplicity of the device, as well as the 10 advantages thereof, will, it is thought, be perfectly apparent to those skilled in the art to which such inventions appertain, without further detailed description.

Having thus fully described the said invention, what I claim is:—

A device of the character set forth including a casing comprising an upper semi-cylindrical member and a lower semi-cylindrical member, said members being hingedly connected at one of their adjacent transverse

end portions, each of said members having its top longitudinal edge flanged, said lower member being provided on the side edge thereof at a point adjacent its flange with upstanding bearings, said upper member 25 having the opposite sides thereof formed with a pocket adapted to receive said bearings upon the closing of said members, a gasket disposed upon the bottom member, and means for locking the sections together, 30 said means also securing the gasket in operative position and preventing any accidental displacement thereof.

In testimony whereof I affix my signature in presence of two witnesses.

CHARLES W. McLAUGHLIN.
